[57] CLAIM

The ornamental design for motorized skateboard, as shown and described.

DESCRIPTION

FIG. 1 is a perspective view of a motorized skateboard showing my new design;

FIG. 2 is a perspective view thereof, with the handle in collapsed condition;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a perspective view of a motorized skateboard showing a second embodiment of my new design;

FIG. 10 is a perspective view of FIG. 9, with the handle in collapsed condition;

FIG. 11 is a left side elevational view of FIG. 9;

FIG. 12 is a right side elevational view of FIG. 9;

FIG. 13 is a front elevational view of FIG. 9;

FIG. 14 is a rear elevational view of FIG. 9;

FIG. 15 is a top plan view of FIG. 9; and,

FIG. 16 is a bottom plan view of FIG. 9.
